UNITED STATES PATENT OFFICE.

BERT R. BENJAMIN, OF OAK PARK, ILLINOIS, ASSIGNOR TO INTERNATIONAL HARVESTER COMPANY OF NEW JERSEY, A CORPORATION OF NEW JERSEY.

GRAIN-HARVESTER.

1,159,887.

Specification of Letters Patent.

Patented Nov. 9, 1915.

Application filed October 9, 1913. Serial No. 794,187.

To all whom it may concern:

Be it known that I, BERT R. BENJAMIN, a citizen of the United States, residing at Oak Park, in the county of Cook and State 5 of Illinois, have invented certain new and useful Improvements in Grain-Harvesters, of which the following is a full, clear, and exact specification.

My invention relates to grain harvesters, 10 and is particularly designed for use in the harvesting of Kafir corn.

The object of my invention is to provide an improved mechanism that will separate the butts of the stalks from the heads and 15 bind them in separate bundles for greater convenience in the handling of the shock.

A further object of my invention is to provide an improved mechanism of the character set forth which is adapted to use in 20 connection with a grain binder of standard construction.

These objects are attained by means of mechanism, one embodiment of which is illustrated in the accompanying drawings, 25 in which—

Figure 1 is a rear elevation partially in section of part of a grain harvester having my invention embodied in its construction; Fig. 2 is a side elevation of Fig. 1; and Fig. 30 3 is a detail view of the stationary knife member.

Like reference characters designate the same parts throughout the several views.

The harvester includes the usual grain 35 platform 1, wheel frame 2, elevator 3, traction wheel 4, and crank shaft 5, which may derive motion from the traction wheel in any preferred manner.

6 represents a grain binder carried by the 40 wheel frame, and 7 the binder deck leading from the delivery end of the elevator to the binding mechanism.

8 represents a common form of binder frame, having a needle shaft 9 and knotter 45 shaft 10 journaled therein, motion being imparted to these shafts in any preferred way.

11 represents the usual knotter head, and 12 the knotter actuating gear, 13 the discharge arms, 14 the breast-plate, and 15 the 50 needle; these parts being common in grain binders.

For the purpose of my invention, the needle shaft is provided with a rearward extension 16, and the knotter shaft is extended 55 rearwardly also.

17 represents a supplemental knotter mechanism carried by the rear extension of the knotter shaft, and the same in all essential elements as the one heretofore described; the mechanisms being separated by means 60 of the sleeve member 18, and 19 represents a supplemental needle that coöperates with the supplemental knotter.

20 represents packer arms moving in orbital paths, that derive motion from the 65 packer shaft 21 in a common way and operate adjacent the needles.

For the purpose of severing the stalks between the knotter mechanisms, a suitable knife is provided. In the embodiment of 70 my invention shown, a knife 22 in the form of a packer arm having a sharpened stubbleward edge is used. This knife is located between the two packers 20 and preferably derives motion from the packer shaft, as 75 shown, although it may be driven independently from some operative part of the machine. Coöoperating with this moving knife, as shown in Figs. 1 and 2, is a fixed coacting knife 23 carried by a bracket 24 8 secured to the binder deck and projecting upwardly from the latter. (See Figs. 1 and 3.)

In operation the stalks are delivered to the packers and knotting mechanism as in 8 common forms of grain binders, and as they are being packed against the trip arm and compressor the movable knife 22, coöperating with the opposing knife 23, severs them between the knotters, thus separating the butts 9 of the stalks from the heads.

It is to be understood, however, that I disclaim the broad combination of the spaced or axially aligned knotting devices with means for severing the stalks between them, or an orbital knife for so cutting the same operating either alone or in coöperation with a fixed knife in such a manner as to sever the stalks in advance of the knotting devices. Nevertheless, while I have shown and described a preferred form of my invention, I do not wish to confine it to the specific details as described, except as limited by the above disclaimer, as many minor changes may be made without departing from the spirit of my invention.

What I claim as my invention, and desire to secure by Letters Patent, is:

1. In combination, mechanism for forming a prostrate bundle, binding mechanism

for binding said bundle at a plurality of points, and means for severing the stalks in said bundle at a point between said binding mechanisms.

5 2. In combination, a binder deck, a plurality of knotting devices spaced apart above the same, and means carried beneath said deck and movable therethrough for cutting the stalks between said knotting devices.

10 3. In combination, a binder deck, a plurality of knotting devices spaced apart above the same, a knife movable through said deck at a point beneath said knotting devices, and an upstanding stationary member on said deck coöperating with said knife.

15 4. In a grain binder, a frame, a binder deck, a plurality of knotting devices carried above said deck, packing mechanism on said frame coöperating with said knotting devices and movable through said deck, and means operatively connected to said packing mechanism for severing the stalks between said knotting devices.

20 5. In a grain binder, a frame, a binder deck, a plurality of alined knotting devices spaced apart above said deck, packing-mechanism carried on said frame coöperating with said knotting devices and movable through said deck, a knife for severing the stalks between said knotting devices, and knife driving connections between said

6. In a grain binder, a frame, a binder deck, a plurality of alined knotting devices spaced apart above said deck, packing mechanism coöperating with said knotting devices and movable through said deck, a knife for cutting the stalks between said knotting devices pivotally connected to said frame, and knife driving connections between said knife and packing mechanism.

7. In a grain binder, in combination, a plurality of axially alined knotting devices spaced apart, a binder deck, packer arms operative above said deck and adjacent each of said knotting devices, a packer driving shaft, and a knife driven by said packer driving shaft and operative to sever the stalks between said knotting devices.

8. In a grain binder, a binder deck, a plurality of axially alined knotting devices spaced apart thereon, packer arms operative above said deck and adjacent each of said knotting devices, a packer driving shaft beneath said deck, a knife driven by said shaft, and a coöperating fixed knife carried by said binder deck coöperating with said movable knife in severing the stalks between said knotting devices.

In testimony whereof I affix my signature, in the presence of two witnesses.

BERT R. BENJAMIN.
